MERCHANTISING PACKAGE

William O. Mashburn, Jr., Cincinnati, Ohio

Application March 14, 1933, Serial No. 660,688

6 Claims. (Cl. 62—91.5)

This invention relates to a merchandising package, objects of which are: to render more convenient than heretofore the offering of bottled beverages for sale in a refrigerated or cooled condition, without necessitating the installation of an ice box or the like; to provide means whereby cooled bottled beverages may be shipped or delivered to a consumer, or to a dealer who possesses no means adequate to maintain the product in a refrigerated condition, to the end that the product may without inconvenience be dispensed, in a cool and refreshing condition, in business offices, homes, at card parties and the like, concessions in the lobbies of buildings and in other places too small or crowded to include an ice box or refrigerating apparatus, on trains, and in air-craft, buses, and other conveyances which heretofore could not carry such commodities due to the impracticability of providing for refrigeration.

Other objects of the invention are, to provide an unique arrangement of bottles in a box having predetermined dimensions governed by the bottle sizes and shapes, whereby cracked ice dropped into the box may be caused to effectively gravitate, through certain channels resulting from the peculiar mode of packing, in order to quickly cool all the bottles either by actual contact thereof with the ice or by convection of cold from one bottle to another, the bottles being peculiarly arranged in contacting relationship; to provide means interiorly of the box for proper distribution of cold from a quantity of solidified carbon dioxide or other refrigerating substance; to provide means for precluding bottle breakage during shipment, said means serving also as a means for spacing the bottles from the extreme cold of the refrigerating substance, and to accomplish the foregoing objects with the use of but few, simple, and inexpensive constituent elements.

The foregoing and other objects are attained by the means described herein and disclosed in the accompanying drawing, in which:

Fig. 1 is a top plan view of the device of the invention.

Fig. 2 is an elevation of the device shown in Fig. 1.

Fig. 3 is a top plan view of the device, with the lid thereof removed, showing the manner of arranging bottles therein.

Fig. 4 is a fragmental cross sectional view taken on line 4—4 of Fig. 1. Fig. 5 is an elevational view of the lid interior, and taken on line 5—5 of Fig. 4.

Fig. 6 is a view of one of the bottles shown in Fig. 3.

Fig. 7 is a view of a different form of bottle capable of use with the device of the invention.

Heretofore, it was customary to merchandise bottled goods such as beverages and the like, by transporting them under ordinary temperature conditions, and delivering them to the consumer or the dealer, so that he was required to maintain a refrigerator or cooling box for cooling the product before it could be offered for sale or consumption. As a result of that practice, it was practically impossible to offer the goods for sale in a cooled condition at many places where there existed a demand for the products. For example, passengers of various types of vehicles, such as air craft, water craft, and certain types of road vehicles, could not be supplied with the beverage in a cooled condition due to lack of facilities for maintaining the chilling means therefor.

In accordance with present invention bottles containing beverages may be very compactly stored and maintained in a cooled condition by the use of common solidified carbon dioxide or other refrigerating substance, or by the application of ordinary cracked ice. The device consists of a rectangular box 12 having side walls 13, end walls 14, and a bottom wall 15, the box being preferably metal covered so as to withstand wear and rough usage. The interior of the box is provided with a metallic liner 16, which covers the inner side, end, and the bottom walls thereof. As is most clearly indicated in Fig. 4, the interior lining extends upwardly to a point 17 which is approximately an inch below the upper circumferential edge 18 of the box. The space between the inner and outer metallic walls of the box is filled with a suitable insulating substance 19 such as cork or the like.

A set of four frame pieces 20, preferably of wood or other material which will hold screws or nails, provides a circumferential frame which is superposed upon the insulating substance 19 and extended from a location slightly below the point 17 to an upper rim in substantial contact with the upper metallic flange 21 at the top edges of the box. The member 20 preferably is made in substantial triangular formation, so that an interior tapered wall 22 may be provided for effecting a tight seal when the lid of the box is disposed in closed position.

As indicated in Fig. 4, the top portion of each vertical wall is covered by means of a channel shaped metallic border piece 23, which includes the top flange 21 and the downwardly directed

inclined wall 22. The member 22 abuts the tapered face 24 of member 20, and the lower edge 25 of said member stops short of the uppermost edge of the circumferential liner 16, so that 5 neither heat nor cold may be conducted between the members 22 and 16. In the space 26 between the circumferential edges 25 and 17, there is disposed a flexible circumferential member 27 which extends inwardly of the box to provide a 10 sealing means between the interior wall of the box and the walls of the lid. The member 27 is a non-conductor of heat, and it includes an upwardly directed flange portion 28 which preferably is clamped between the members 22 and 20. 15 and to be held in the proper position at a given elevation within the box.

By reason of the resiliency of the insulating material 19, the various walls of the inner lining are permitted to flex and expand so that a series 20 of bottles may be tightly arranged therein in the manner disclosed in Fig. 3. It is to be observed that the bottoms 29 of superposed overlapping bottles are arranged to contact the sides of the inner liner, the bottles being so arranged that the 25 neck of one overlaps the neck of another for a distance approximating half the length of the bottles. The necks of the bottles are indicated at 30. By referring to Fig. 3, it will be observed that the length of the box is not equal to the 30 diameters of a row of adjacent contacting bottles, but rather to a length determined by the combined diameters of a row of bottle bodies to which is added the combined diameters of the cap ends of opposed bottles which are disposed therebetween. 35 The width of the box is determined by the amount of overlap between the necks of opposed bottles whose bottoms 29 are disposed against the side walls of the box.

In one embodiment of the invention each bottle 40 comprises a bottom 29 and a constricted neck portion 30, intermediate which parts is an expanded or enlarged body portion 31, which may be referred to as an enlarged shoulder portion, and intermediate this shoulder portion and the 45 bottom 29, there is formed the reduced body portion 32. The base is larger than the reduced body portion, and its diameter approximates the diameter of the enlarged shoulder portion 31 of the bottle. Thus it will be apparent that when 50 the bottles are placed horizontally within the box with their bottoms abutting opposite side walls of the box interiors, the necks of one group of bottles will be received between the necks of the oppositely disposed group, all in a common 55 plane parallel to the box bottom. The necks of one group of bottles are sufficiently advanced between the necks of the other group, to provide the space between alternate bottles for reception of a cooling substance, such as cracked 60 ice. The reduced portions 32 of the various horizontal layers of bottles serve to provide zig-zag passages from the top layer to the bottom layer through which passages the cracked ice may 65 gravitate and thereby reach all the bottles in the box. All the bottles being thereby disposed in contacting relationship, it is plainly evident that the cold of the cooling medium, and that of any bottle or group of bottles will be conveyed 70 throughout the entire content of the box. The flexible inner walls of the box provide for a tight packing of the bottles so that relative movement thereof is practically eliminated, wherefore the merchandising package will withstand rough handling without breakage of the bottles contained 75 therein.

It will be readily understood that bottles of the type indicated in Fig. 7, and the other bottles having a reduced neck portion, may advantageously be packed within a cooling device in the manner just described.

The lid for the box may be constructed by the use of a rectangular frame work of members 33 which provide an interior space for the reception of an insulating substance 34 such as cork or the like. The substance is confined within the space by means of the outer wall 35 and an inner wall 36. The sheet or wall 35 may be held in position against the frame members 33 by means of angular members 37 which may be screwed or otherwise secured in place by means of fasteners 38. 10 The inwardly directed flanges 37 of the angular members extend for a distance exteriorly of the face 40 of each frame member, to an inclined portion 41 thereof. The circumferential flange 42 of the inner plate or wall 36 is adapted to hold in position a cushioning or sealing member 43, which encircles the lid so as to co-operate with the continuous sealing member 27 of the box interior. The member 43 is a heat non-conductor, and it will be observed that no part of the inner plate 20 25 36 contacts the metallic part of the outer members 39 and 35 in such a manner as would permit convection of heat or cold. The members 33 are non-conductors of heat and cold.

One side edge 44 of the lid preferably has attached thereto by any suitable means, such as screws or the like 45, a piano hinge 46 that has one of its legs 47 screwed or otherwise secured to the box interior.

The inner wall 36 of the lid is adapted to support a substantially rectangular container 38, preferably of metal, for the storage of solidified carbon dioxide or other refrigerating substance. The container 48 is of a depth so calculated as to dispose the bottom 49 thereof in spaced relation 40 with the upper layer of bottles when the lid is closed upon the box. This construction is necessary to preclude freezing of the contents of the bottles.

Each of the three sides 50, 51 and 52 of the container is provided with an outwardly extending flange 53 which is adapted to enter suitable guide means for holding the flanges in contact with the metallic wall 36. The guide means may be constituted of a series of three members 54 of substantially S-shape, one of the legs 55 of which is fastened to the plate 36 or to both the plate and the frame member 33, by any suitable means such as screws 56. Those guide members 54 which extend longitudinally of the lid are disposed in substantial parallelism, so that the legs 57 thereof may provide supports for the opposite flanges 53 of the container. The end guide member 54 has an inwardly directed leg 58 spaced sufficiently from the member 36 to provide a support for the end flange 53 of the container.

In order that the bottles may not be displaced in the event that the box be inverted, the interior of the lid is provided with a pair of spaced members 60, which extend downwardly from the lid interior for a distance sufficient to contact the reduced portions 32 of the top layer of bottles. The members 60 also extend beyond the bottom of the container 48, so that the bottles may not rest upon the container even though the box be inverted. 70 The purpose of this construction is to preclude freezing of the contents of the bottles, and accordingly, the members 60 are made of non-conducting material. Although the spacing members 60 are shown herein as being attached to the guide 75

members 54 by means of screws 61, it is to be understood that these spaced members may be mounted upon other parts of the lid interior so long as they will perform their intended function.

5 Any suitable means may be provided for latching the lid in its closed position, there being shown one form of such means. The means disclosed comprise a disc 62 which is rotatably mounted exteriorly of the lid within a depression 63 thereof, the disc being provided with an operating handle 64 that may lie wholly within the depression. Pivotally mounted at diametrically opposite points 65 of the disc, are the latch members or bolts 67, each of which has an end 68 adapted to enter 10 suitable openings 69 in the end walls 14 of the box. It is to be understood that the invention is not to be limited to the above type of latching means.

If desired, the end walls of the box may be provided with handle members 70. These handle 20 members may or may not be located within depressions 71 provided in the end walls of the box.

It is to be understood that various modifications and changes in structural details of the device 25 may be made, within the scope of the appended claims, without departing from the spirit of the invention.

What is claimed is:

1. The combination of a box and a series of individual contacting bottles, the bottles being placed horizontally within the box with their bottoms abutting opposite side walls of the box, the necks of one group of bottles being received 30 between the necks of the oppositely disposed group of bottles, all in a common plane parallel to the box bottom, with the necks of one group of bottles sufficiently advanced between the necks of the other group to provide a space between alternate bottles for reception of a cooling substance, a freezing means, and a fixable member 35 formed of material known to be a non-conductor of heat, arranged to contact the sides of certain ones of the bottles and to maintain them in the above stated relationship spaced from the freezing means.

45 2. The combination of a box and a series of individual contacting bottles, the bottles being placed horizontally within the box with their bottoms abutting opposite side walls of the box, the necks of one group of bottles being received 50 between the necks of the oppositely disposed group of bottles, all in a common plane parallel to the box bottom, with the necks of one group of bottles sufficiently advanced between the necks of the other group to provide a space between alternate bottles for reception of a cooling 55 substance, a fixable member formed of material known to be a non-conductor of heat arranged to contact the sides of certain ones of the bottles and to maintain them in the above stated relationship, a lid for the box, and a cooling substance supported by the lid to radiate its cold interiorly of the box, said cooling substance being spaced from the bottles by means of the fixable member to preclude solid freezing of the bottle 60 contents.

70 3. The combination of a substantially rectangular metal lined box and a series of individual contacting bottles each of which has a neck, an adjacent enlarged shoulder portion, a reduced body portion and a base larger than the reduced body portion, the bottles being placed within the box with their bases abutting opposite side walls of the box, the necks of one group of bottles being received 65 between the necks of the oppositely

disposed groups of bottles, all in a common plane parallel to the box bottom, the reduced body portions of alternately disposed bottles being in coincidence to provide a space for reception of ice particles, a similar layer of bottles arranged in the manner just stated, superposed upon the first layer but in staggered relationship, whereby to extend the passage space formed by the reduced body portions of the bottles, and a lid including a container for a cooling substance and means adapted to apply a force to the sides of the upper layer of bottles for precluding relative shifting of the prearranged groups of bottles while at the same time maintaining the bottles at a non-freezing distance from the cooling substance. 15

4. The combination of a substantially rectangular metal lined box and a series of individual contacting bottles each of which has a neck, an adjacent enlarged shoulder portion, a reduced body portion and a base larger than the reduced body portion, the bottles being placed within the box with their bases abutting opposite side walls of the box, the necks of one group of bottles being received between the necks of the oppositely disposed groups of bottles, all in a common plane 20 parallel to the box bottom, the reduced body portions of alternately disposed bottles being in coincidence to provide a space for reception of a cooling substance, a similar layer of bottles arranged in the manner just stated, superposed upon the 25 first layer but in staggered relationship, whereby to extend the passage space formed by the reduced body portions of the bottles, a lid adapted to apply a force to the sides of the upper layer of bottles for precluding relative shifting of the prearranged groups of bottles, a cold conducting and distributing sheet disposed interiorly of the lid and insulated from the exterior of the lid, and a metallic carrier for a cooling substance secured 30 to said conducting and distributing sheet. 35

5. In combination, a box for holding bottles disposed in a horizontal contacting position, insulated walls and a lining for the box, a lid for the box and means associated with the lid for securing the lid in place upon the box, a container for a freezing compound normally fixed relative to the lid interior, guide means upon which the container may be slid to disassociate the container from the lid, and spacing means supported by the lid and depending therefrom to a position below the container for freezing compound, for contacting the sides of bottles packed within the box to preclude shifting of said bottles and to space the bottles always from the freezing compound container. 45 50 55

6. In combination, a box for holding bottles disposed in a horizontal contacting position, insulated walls and a lining for the box, a lid for the box and means associated with the lid for securing the lid in place upon the box, a container for a freezing compound normally fixed relative to the lid interior, guide means upon which the container may be slid to disassociate the container from the lid, and spacing means supported by the lid and depending therefrom to a position below the container for freezing compound, for contacting the sides of bottles packed within the box to preclude shifting of said bottles and to space the bottles always from the freezing compound container, said spacing means being a poor conductor of cold so as to preclude direct convection of cold to the bottles through said spacing means. 60 65 70 75
